UNITED STATES PATENT OFFICE.

GUY L. WOODJARD, OF SAN DIEGO, CALIFORNIA.

SPRING-OILER.

1,183,416.

Specification of Letters Patent. Patented May 16, 1916.

Application filed February 3, 1916. Serial No. 75,949.

To all whom it may concern:

Be it known that I, GUY L. WOODJARD, a citizen of the United States, residing at San Diego, in the county of San Diego and State of California, have invented certain new and useful Improvements in Spring-Oilers, of which the following is a specification.

My invention relates to a device for lubricating springs for vehicles and the like, and the objects of my invention are, primarily, improvements over my application for spring oilers, filed in the United States Patent Office January 5, 1916, Serial No. 70,387, and the objects of said improvements are: First, to provide a device of this class which increases the oil reservoir space; second, to provide a device of this class in which the oil hole cover is simpler, more efficient and not so liable to get out of order; third, to provide a device of this class which is more simple of construction, durable, and efficient; fourth, to provide a device of this class which allows relief for the oil centrally at the sides so that it flows more freely at the middle of both sides than at other portions of the device; and fifth, to provide means for closing the ends of the device, thus adding to its durability.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of the specification, in which:

Figure 1 is a perspective view of the preferred form of the device shown mounted on a spring ready for use. Fig. 2 is a top or plan view of the preferred form of the device. Fig. 3 is an end view thereof. Fig. 4 is a longitudinal sectional view thereof. Fig. 5 is a bottom view thereof. Fig. 6 is a top or plan view showing the metallic raised portion in a slightly modified form from that shown in Figs. 1, 2, 3, 4, and 5 of the drawings. Fig. 7 is an end view thereof. Fig. 8 is a top or plan view of the device in a slightly modified form from the other figures of the drawing. Fig. 9 is an end view thereof, and Fig. 10 is a longitudinal sectional view thereof.

Similar characters of reference refer to similar parts throughout the several views.

The casing 1, pad 2, oil hole cover 3, and shield 4 constitute the principal parts of my oiler.

The casing 1 consists of a rectangularly shaped piece, preferably metallic, provided with downwardly extending right-angle flanges 1^a, which are provided with inwardly extended portions 1^b along their lower edges. These portions 1^b are adapted to fit into the usual slight grooves between the two upper spring leaves and hold the device in position on the upper spring leaf. The main portion is provided at each end with downwardly extending ridges 1^c formed integrally in the metal. It is also provided with a raised portion 1^d which increases the capacity of the oil reservoir and may be rectangularly shaped as shown in Figs. 2 and 8, or diamond shaped as shown in Figs. 6 and 7 as desired, as it is obvious that different shapes may be pressed into the top of this metallic case for increasing the capacity of the reservoir and for allowing freer seepage of the oil in the middle on each side than at other portions. In this raised portion 1^d, is provided an oil hole 1^e against the under surface of which is secured a spring blade 3 some distance from said hole, so that the loose end by reason of the inherent spring of the material will close the hole 1^e but may be pressed down for admitting oil through said hole but will prevent dirt from entering the oil reservoir through the hole 1^e.

Mounted on the lower surface of the main portion 1 and between the two flanges 1^a is a pad preferably of felt provided with a central hole 2^a of suitable size to contain a sufficient quantity of oil. This pad 2 is sufficiently compressed to make a tight fit between the upper surface of the upper spring leaf and the lower surface of the main portion of the casing 1 but will allow the oil to seep out gradually along the sides and run down between the leaves of the spring when the springs are in operation. The ridges 1^c will cause the ends to be considerably tighter and prevent seepage out through the ends. In the modified form of construction shown in Fig. 6 of the drawing the enlarged portions extend to the sides of the main portion, thus allowing relief of the pressure on the pad so that the oil will flow more freely at the middle of the device than at any other portion.

In the modified form of construction shown in Figs. 8, 9, and 10 of the drawing

there is placed a shield 4 between the pad 2 and the spring and the ends are turned up at 4^a, thus inclosing the pad in the end, forming a complete metallic casing for the 5 pad and oil reservoir, but being loose enough to allow the oil to seep down between its sides and the flanges 1^a on the casing.

Though I have shown and described a 10 particular construction with slight modification, I do not wish to be limited to this particular construction and to the modifications therein shown and described, but desire to include in the purview of my invention the construction combination and arrangement substantially as set forth in the appended claims, as it is obvious that slight modifications may be made in the form 15 without deviating from the invention.

20 It is obvious that with this construction there is provided an oiler for springs which will allow the oil to seep down between the leaves of the spring when said springs are in operation, that by particular shapes in 25 the enlarged portion of the casing relief is given to the pad so that the oil will have freer movement near the middle of the casing on each side than in other portions, that the ridges 1^c provide means for increasing 30 pressure on the pad at the ends for preventing leakage at the ends, that the shield 4 provides means for closing the ends so that the pad is covered and completely incased thus adding to its durability.

35 Having thus described my invention what I claim as new and desire to secure by Letters Patent, is:

Copies of this patent may be obtained for five cents each, by addressing the "Commissioner of Patents, Washington, D. C."

1. In a spring oiler, the combination of a casing provided with side members adapted to fit over the upper leaf of the spring, with 40 integral ridges in each end thereof, and with an integral raised portion on the upper surface thereof, and a resilient pad provided with a central hole for an oil retainer.

2. In a spring oiler, the combination of a 45 casing provided with side members adapted to fit over the upper leaves of the spring with integral downwardly extending ridges in each end thereof and with an upwardly extending portion on the upper surface 50 thereof provided with an oil hole therein, means secured therein for covering said oil hole and a resilient pad provided with a central hole for an oil reservoir.

3. In a device of the class described, the 55 combination of a casing adapted to fit over the upper leaf of a spring, provided with a raised portion on the upper surface thereof for increasing the oil capacity and a felt pad provided with a central hole therein 60 mounted between the top portion of said casing and the upper surface of said spring.

4. In a device of the class described, the 65 combination of a casing adapted to fit over the upper leaf of a spring provided with a raised portion on the upper surface thereof for increasing the oil capacity and means 70 mounted in said casing for forming an oil reservoir between said casing and the upper spring leaf.

In testimony whereof, I have hereunto set my hand at San Diego, California this 24th day of January 1916.

GUY L. WOODJARD.
